FIG. 1.

1

2,774,311

CONSTRUCTION OF TOY LOCOMOTIVE

Jack H. Berry, Chicago, Ill.

Application July 29, 1953, Serial No. 370,980

3 Claims. (Cl. 105—99)

The invention relates to improvements in the construction of toy locomotives, in particular the method by which the rotary motion of an electric motor shaft mounted within the toy locomotive may be transferred smoothly and continuously down to the traction wheels of the toy locomotive. Previous designs of small scale toy locomotive power transfer mechanisms transmit a considerable portion of the electric motor shaft torque to the locomotive traction trucks as a whole thus forcing the entire toy locomotive body from riding in a true vertical position over the truck, and further, forcing the traction trucks out of true axial alignment with the locomotive body when the toy locomotive is in motion. My invention eliminates these undesirable characteristics of previous toy locomotive power transfers and permits the construction of a toy locomotive which much more closely simulates the operating characteristics of actual locomotives. Furthermore, the electric motor for powering the toy locomotive may be mounted with shaft horizontal in the locomotive body; with a double ended electric motor, that is one possessing shafts extending from either end, more than one locomotive truck may be powered, thus giving greater traction to the toy locomotive and more closely approximating the traction characteristics of an actual locomotive in a small scale toy model.

My invention may be used in scale models of locomotives or in toy locomotives. The purpose of the invention is to obtain a method of transferring the motive power of a rotating shaft powered by an electric motor mounted within the locomotive body down through the locomotive power trucks but yet preserve all the degrees of freedom of linear motion and rotation for the truck wheels and for the truck as a whole which is characteristic of conventional locomotive design. These objectives are realized by forming the truck king pin in such a way that it is hollow and will permit a coaxial vertical drive shaft to rotate freely within it, and so designing the king pin that it is formed or cast as an integral part of the truck bolster.

With the foregoing and other objects in view, the present improvements will be understood as capable of embodiment in a wide variety of structural forms from which I have chosen to illustrate herein a preferred example which will be understood in fuller detail from the following description having reference to the accompanying drawings herein:

Figure 1 is a side elevation of a toy locomotive traction truck and parts of the locomotive frame embodying the present improvements. Parts are in section and parts are cut away. A short section of track which the locomotive runs on is also shown.

Figure 2 is a cross section of the locomotive truck taken along the line 2—2 in Figure 1.

Figure 3 is a vertical section of the locomotive truck taken along the line 3—3 in Figure 2.

Figure 4 is an elevation of the end of the journal box and section of the side frame showing the mounting of

2

the journal box and spring and their relationship to the side frame.

A small horizontally mounted electric motor shaft 10 is fastened by means of a shaft coupling 11 to a second horizontally mounted shaft 12. The shaft 12 is fitted with a small beveled gear 13. This shaft 12 with its beveled gear is mounted in suitable bearings 14, 14 held in the locomotive frame. The small beveled gear 13 engages a second larger beveled gear 15 mounted on a vertical shaft 16 and held in proper alignment by means of a small bearing 17. The vertical shaft 16 is provided with a small pinion gear 18 which engages a second gear 19 mounted on a second vertical shaft 20. This second vertical shaft 20 is passed vertically through the king pin 21. The entire locomotive truck pivots freely about the center of its king pin 21. The king pin 21 is an integral part of the bolster 22 of the truck as is shown in both Figure 1 and Figure 3. The short vertical shaft 20 which passes axially through the center of the king pin 21 terminates in a small beveled pinion gear 23. This pinion gear 23 engages a second beveled gear 24 mounted on a shaft 25 in a horizontal position and in the same horizontal plane as the two truck axles 26. The horizontal shaft 25 is mounted in the center, axially, of the truck and transmits torque to small beveled pinion gears 28 attached at either end. This shaft 25 is held in proper position by bearing surfaces 30 framed in the bolster 29 and assembled by removing the top and bottom portions of the bolster casting which join on the same horizontal plane in which the center line of shaft 25 lies and are designated in the accompanying drawing as a plane surface 34. The truck axles 26 are mounted within a gear box 31, the ends of the axles pass out either side of the gear box and through bearings 32.

The gear box itself is held to the bolster by means of a small collar section 33 which is an integral part of the bolster. However, the gear box is free to rotate about an axis 4—4. This degree of rotational freedom in the gear box permits the wheels 35 and axles 26 upon which the wheels 35 are rigidly attached to adjust to small irregularities in the track 36. To facilitate assembly of the gear box 31 and its interior parts gears 28, 27 and axles 26, and also to permit mounting on bolster collar 33, the gear box is composed of two castings, one top and one bottom section, fastened together in assembly by small screws 37. The gear box 31 is held onto the bolster collar 33 by a small gear box collar 38 which interlocks with the bolster collar 33 as is shown in Figure 2.

The side frames 39 are held in place by means of two small pins 40, about which the bolster has a small degree of freedom to rotate in adjustment to axial pitching motions of the truck as a whole. The small pins 40 pass through suitable holes in the bolster and into suitable holes prepared in the side frame.

The axles 26 terminate in journal boxes 41 which ride vertically in a small slot in the side frame 39 as is illustrated in cross section by Figure 3 and in an elevation Figure 4. Small springs 42 hold the side frame in suspension about the journal boxes. A small steel staple 43 prevents the journal box from dropping out of the bottom of the journal slot in the side frame 39. This arrangement permits the individual wheels to raise and lower in adjustment to irregularities in the track 36, but without transmitting those adjustments as violent rocking motions to the entire truck and in turn to the locomotive body.

The several degrees of freedom described in this embodiment of my improvements permits a small, continuous transfer of torque from a horizontal rotating motor shaft down to the traction wheels of a locomotive truck,

while at the same time preserving a response to the irregularities of the track in a manner which is in a striking similitude to the performance observed in actual locomotives during their movements along an irregular section of track.

A second aspect of my invention makes possible the smooth continuous transfer of rotating shaft power to the wheel axles even during an instant when the wheels are responding to an irregularity in the track by adding a small vertical component to the individual wheel motion. The ends of each wheel axle are rested in a small journal box. This small journal box is held between vertical guides in the side frame but remains free to move in response to irregularities in the track. The journal box is held in its normal position by a small compression spring 42 located in a recess within the side frame and the top of the journal box. This is best shown in Figure 4. Within the gear box 31, power is transferred from a horizontal shaft 25 located within the truck bolster, but extending outward axially with the truck, terminating in a suitable bevel gear 28 which contacts and drives a second bevel gear 27 fastened to the wheel axles. In order that the wheel axle bevel gear will at all times be so located that it contacts and meshes with the driving gear 28, the wheel axles 26 are held within the gear box 31. In order that the wheels and their axles may retain the freedom of motion permitted by the journal box design described above, the gear box 31 is held in position next to the bolster by a collar which permits the entire gear box 31 complete freedom of rotation about a line 4-4 coaxial with its drive shaft 25. In order that the gear box 31 will remain in its proper alignment with drive shaft 25, rather large bearing surfaces must be provided on the rotating collar parts 29 and 38 as shown in Figure 2.

What is claimed is:

1. A toy locomotive traction truck comprising a unitary bolster and hollow king pin, the bolster portion being hollow, having end walls and formed by an upper member and a lower member meeting along a horizontal plane passing through the midportion of the bolster, a freely rotating vertical shaft passing through the king pin and terminating within the interior of the bolster, the bolster being provided with a horizontal opening in either end wall centered on the said horizontal plane and surrounded with protruding collar members having enlarged portions in spaced relationship with the bolster end walls, a rotatable horizontal unitary shaft mounted in the said horizontal plane within the bolster and extending through and beyond the said end wall holes, the vertical shaft being connected by gear means to the horizontal shaft, hollow gear boxes having end walls formed by an upper member and a lower member joined along a horizontal plane in their midportion, the gear boxes further provided with openings centered on the said horizontal plane and in the end walls, said openings being adapted to interlock with the said bolster collars forming a rotatable mounting, axles mounted within the gear boxes extending beyond the sides thereof and centered on the said horizontal plane, the horizontal shaft being connected by gear means to the axles, whereby rotary motion induced

in the vertical shaft may be transferred to the axles independently of rotation of the bolster about the axis of the king pin and independently of rotation of the axles about a horizontal axis at right angles to the said axes.

2. In a toy locomotive traction wheel truck having side frames, movably mounted journals in the side frames, axles having ends journaled in the journal boxes, wheels fixedly mounted to the axles, all in combination with three gear boxes each having end walls and being formed by upper members and lower members joined on a horizontal plane in the mid regions of the gear boxes and positioned between the side frames and adjacent one another end to end, openings in the end walls of the gear boxes centered on the said plane, collar members extending axially outward around the openings in the center gear box and having enlarged portions in spaced relationship to the end wall of the center gear box, the openings in the end gear boxes being adapted to interlock about the center gear box collar members to prevent axial movement of the gear boxes with respect to one another, but to permit rotational movement with respect to one another, a horizontal rotatably mounted unitary shaft extending through the center gear box, through the end wall openings in the end gear boxes and having either end terminate within one end gear box, the said axles being rotatably mounted in the end gear boxes centered on the said horizontal plane and extending laterally beyond the sides of the gear boxes into the journal boxes, gear means connecting the horizontal shaft and the axles, the gear boxes being supported between the side frames by means of a single pin protruding symmetrically from each side frame, and a rotatable vertical shaft connected by gear means to the horizontal shaft in the center gear box and extending symmetrically upward through the upper member of the center gear box, whereby rotary motion may be transferred from the vertical shaft to the wheels on the axles irrespective of vertical motions of the individual journal boxes within the side frames.
3. In a toy locomotive the combination of a gear box having sides and ends, an axle rotatably mounted within the gear box, the ends thereof extending beyond the sides of the gear box, means for rotatably mounting the gear box on its end wall and having an opening co-axially disposed within the rotatable mounting, a horizontal shaft in the plane of the axle rotatably mounted at right angles to the axle within the opening and extending therethrough, gear means connecting the axle and the shaft whereby rotary motion may be transferred from the shaft to the axles independently of the small rotational movements of the axle about the center of the shaft.
